UNITED STATES PATENT OFFICE.

SOL. S. SONNEBORN, OF BROOKLYN, NEW YORK, ASSIGNOR TO HOPEWELL INSULATION & MFG. CO., INCORPORATED, A CORPORATION OF VIRGINIA.

CONDENSER CEMENTED SECTIONAL INSULATOR.

1,426,421.

Specification of Letters Patent. Patented Aug. 22, 1922.

Application filed February 27, 1917. Serial No. 151,364.

To all whom it may concern:

Be it known that I, SOL. S. SONNEBORN, a citizen of the United States, and a resident of Brooklyn, county of Kings, and State of New York, have invented certain new and useful Improvements in Condenser Cemented Sectional Insulators, set forth in the following specification.

This invention relates to sectional high-potential insulators of the type adapted to be mounted on a pin.

The object of the invention is to increase the puncture strength of a plurality of nested insulating sections by distributing as uniformly as possible the electro-static stress over the surfaces of the nesting portions. A furthermore specific object is to accomplish this distribution of electro-static stress by employing a filling or cementing compound of such a character as to serve two purposes, that of mechanically uniting the nesting parts and that of providing an electrically conducting partition between the insulating partitions. Heretofore, on page 923 of Part I, volume 32 of the Transactions of the American Institute of Electrical Engineers, a condenser type insulator has been described as built up of a series of substantially bell-shaped metallic shells, spaced apart but nesting and the spaces therebetween filled with a moulded dielectric compound. This theoretical suggestion is impracticable in the construction of a commercial insulator and it is specifically an object of my invention to attain substantially the same beneficial result in the way of stress distribution by employing standard vitrified porcelain sections, but instead of cementing them together with an insulating cement, mechanically to unite them one to the other by a metallic filling and either to extend the metallic filling as a conducting canopy over the flaring petticoats or electrically to connect a separate metallic canopy enclosing a petticoat directly to the metallic filling so that, in effect, a bell-shaped metallic shell is interposed between each two adjacent nested insulating sections.

The above will better be understood by reference to the accompanying claims and the illustrative embodiments of my invention which are described in the following specification in connection with the figures of the accompanying drawing, which forms a part hereof and in which like characters desig-

nate corresponding parts in the figures, and in which Fig. 1 is a vertical elevation partly in vertical section of one illustrative embodiment of my invention; and Fig. 2 is a fractional view in vertical section illustrating one of the many possible modifications of my invention.

The insulator A is shown built up from a plurality of insulating sections 1, 2 and 3. So far as my invention is concerned, the exact number is immaterial. I have illustrated standard sections of a commercial type of pin insulator. The first or bottom section 3 comprises a cup-shaped portion 4, suitably formed such as with threads to take the pin 5 and having exterior corrugations 6. This insulating section 3 also comprises a flaring petticoat 7. A second or next outer section 2 comprises a cup-shaped portion 8, adapted to nest over the cup-shaped portion 4 and having internal and external corrugations 9 and 10. The section 2 also comprises a flaring petticoat 11. The outer section 1 comprises a cup-shaped portion 12 and a flaring petticoat 13, the cup-shaped portion having internal corrugations 14 and a seat 15 for supporting a conductor. It is to be understood that the corrugations formed on the adjacent surfaces of the cup-shaped sections need not, of necessity, be corrugations, as any provision tending to lock the parts together through the medium of filling is contemplated.

The filling, which has heretofore been a highly insulating cement, in the case of my invention, as illustrated by the fillings 16 and 17, is metallic. It may be formed in any suitable manner such as by pouring molten lead or a conducting alloy into the spaces between two nested portions, the same being inverted during the process; or the filling may be formed from a suitable metallic amalgam such as a zinc mercury amalgam; or the filling may be formed out of a plastic metallic cement, the principal base of which is a pulverized or granulated metal.

Before the assembling of the various sections going to make up the insulator, sheet metal sheaths such as 18 and 19, preferably formed to conform to the surfaces of the petticoats for which they are designed, may be applied to the petticoats, as for example, to the petticoats 7 and 11 respectively. When the metallic fillings 16 and 17 are formed the filling may have a portion

such as the portion 20 for the filling 16 and the portion 21 for the filling 17, which is caused electrically and mechanically to unite with the respective metallic sheaths 18 and 19. If desired, the portions 20 and 21 may be soldered. In other words, the sheaths 18 and 19 may be soldered directly to the metallic filling, in which case a chemical union in addition to an electrical and mechanical one is made. It is also comprehended that, if the sheets are made of zinc, it is possible to make a chemical union between the cement and the zinc amalgam filling.

In Fig. 2 I have shown a modification in which the filling 170 is itself continued and flared into the sheath 190 about the surface of the petticoat 7.

What I claim and what I desire to secure by United States Letters Patent is:

1. A high-potential insulator of the condenser type comprising a plurality of insulating sections, each section comprising a cup-shaped portion, the cup-shaped portions being nested one within the other; one or more of the inner sections having a petti-

coat; a metallic filling covering the entire surface of a nested cup-shaped portion of a section and mechanically uniting it with the next outer cup-shaped portion; and a metallic sheath covering the petticoat portion of said section and in electrical connection with said metallic filling.

2. A high-potential insulator of the condenser type comprising a plurality of insulating portions in the form of solids of revolution having each a cap-part and at least one a petticoat-part also, the cap-parts being arranged to nest one within another; and a metallic sheath covering each combined cap-part and petticoat-part, at least the portion of said sheath between nesting cap-parts being a moulded metallic filling, all whereby each said metallic sheath increases the condenser action and the moulded portion also serves as a mechanical binder for the cap-parts.

In witness whereof I have signed my name to this specification, this 16th day of February, 1917.

SOL S. SONNEBORN
